UNITED STATES PATENT OFFICE.

JOSEPH W. DAWSON, OF ST. LOUIS, MISSOURI, ASSIGNOR TO BARRY-WEHMILLER MACHINERY COMPANY, A CORPORATION OF MISSOURI.

BOTTLE-CARRIER.

1,200,924.

Specification of Letters Patent. Patented Oct. 10, 1916.

Application filed October 7, 1915. Serial No. 54,510.

To all whom it may concern:

Be it known that I, JOSEPH W. DAWSON, a citizen of the United States of America, a resident of the city of St. Louis, State of Missouri, have invented certain new and useful Improvements in Bottle-Carriers, of which the following is a full, clear, and exact description, reference being had to the accompanying drawings, forming a part of this specification.

My invention relates to improvements in bottle carriers, particularly adapted for use in bottle soaking machines of the type shown in Patent No. 981,962, Wehmiller & Dawson, Jan. 17, 1911.

Generally stated, the objects of the invention are to improve several features of the machine shown in the prior patent.

The prior structure includes bottle holders in the form of buckets which travel into a liquid receptacle, the bottle holders being guided in their movements so that the bottles passing into the liquid receptacle will fill with liquid and thereafter discharge their contents into said receptacle. The bottles are loosely supported in the buckets of the earlier structure, and as they travel downwardly into the liquid, the loose bottles slide along a wall of the receptacle. In actual practice, I have found that bottles are some times retarded by frictionally engaging the receptacle wall, and as the bottle holder continues its movement, the retarded bottle is liable to be crushed or otherwise injured. It may also be noted that the earlier machine is adapted to receive bottles of different dimensions, but if the buckets are large enough to receive the largest standard milk bottle, they are not well adapted to carry a small cream bottle in the manner it should be conducted through the liquid. Therefore, one of the objects of the invention is to produce a bottle carrier of this type adapted to serve as a most efficient means for conducting any of the various standard milk and cream bottles through the cleansing fluid.

Another object is to provide a bottle carrier having shock absorbers for preventing breakage when the bottles are introduced into the bottle holders. The shock absorbers I have shown are also adapted to prevent the bottles from being injured while they slide along the wall of the liquid receptacle.

A further object is to produce a bottle holder having tubular bottle receiving stems which extend into the bottles to serve as air vents, thus permitting the bottles to fill quickly when they enter the liquid, also permitting them to empty quickly when they pass from the liquid.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a side elevation, partly in section, illustrating a bottle soaking machine equipped with a bottle carrier constructed in accordance with the invention. Fig. II is a top or plan view of the machine shown in Fig. I, the middle portion of the structure being broken away. Fig. III is a detail view of one of the bottle holders. Fig. IV is an enlarged vertical section on line IV—IV, Fig. III.

To illustrate the invention I have shown a tank A adapted to receive caustic-soda solution, or other cleansing liquid, side frames 1 mounted on said tank, a power shaft 2 journaled in said side frames, an idle shaft 3 adjustably supported by bearings 4, and a shaft 5 located within the tank A. The means for driving and guiding the bottle carrier also includes sprocket wheels 6 fixed to the shaft 2, sprocket wheels 7 fixed to the shaft 3, and sprocket wheels 8 fixed to shaft 5. The bottle carrier comprises a pair of sprocket chains 9 each of which passes around the sprocket wheels at one side of the machine. The bottle holders include a series of connecting bars 10 extending across the machine and secured at their ends to the sprocket chains 9. Each connecting bar 10 is provided with a row of tubular bottle-receiving stems 12 and shock absorbers B associated with said stems. The inner end of each tubular stem is screwed into a connecting bar 10 (Fig. IV), and for a purpose which will be hereinafter described, the longitudinal passageway 12' of each stem is open at both ends of the stem. Each shock absorber B is preferably a helical spring 110

having its inner end secured to a stem 12, as shown at 13 in Fig. IV. The outer end portion of each shock absorber extends beyond the outer end of the tubular stem with which it is associated, and the coils of this extended portion are closely fitted together, the resiliency of the shock absorber being due to the separated coils 14. The object in closely fitting the coils to each other at the outer end of each shock absorber is to produce a flexible extension 14', having its elements so arranged that the adjacent end of the stem 12 will not be accidentally caught between them.

Fig. III shows that the bottle holders are adapted to receive the various standard milk and cream bottles, and that the bottoms of the different bottles will lie in substantially the same horizontal plane. The bottles are introduced onto the bottle holders at the point C (Fig. I) and discharged therefrom at the point D. The shock absorbers B engage the bottoms of the bottles to prevent breakage when the bottles are placed on the bottle holders. In passing downwardly from the point C, the bottles are tilted and permitted to engage the vertical wall 15 of the tank A. It will be understood that the bottles are loosely supported by the bottle holders and that the wall 15 serves as means for retaining said bottles on the holders. The bottles are frictionally engaged with the wall 15, and if accidentally retarded by such frictional engagement, they will be yieldingly pushed along by the free end portions of the helical springs which lie within the bottles at points near their lower ends. The bottles also slide along the curved bottom wall 16, and the power for forcing the bottles along this wall is transmitted through the helical springs. After passing to a point opposite the wall 16, the bottle holders are tilted, and the bottles drop by gravity to positions wherein they will not engage said wall.

17 designates curved tracks for guiding the sprocket chains 9 at the discharge point D. As the chains pass over these tracks the bottle holders are tilted in such a manner that the bottles will drop by gravity onto a runway 18 leading to a rinsing tank 19. The bottle carrier moves very slowly, so that the bottles are subjected to the action of the liquid for a considerable period of time, and owing to this extremely slow movement, all of the bottles may not drop from the bottle holders at the predetermined discharge point, unless they are acted upon by some force which will positively release them from the bottle holders. I, therefore, guide the sprocket chains in such a manner that the bottle holder at the discharge point will strike another bottle holder to positively release the bottle at the predetermined point. In Fig. I I have shown a bottle holder ap-

proaching the point at which the bottles are to be discharged therefrom, and it will be noted that this bottle holder is moving in the direction of the arrow 20, while another bottle holder is moving downwardly as indicated by the arrow 21. Obviously, the bottle holder from which the bottles are to be discharged will strike the other bottle holder with the result of shaking the bottles to positively release them at the discharge point.

When the bottles enter the liquid in tank A, they are tilted as shown by dotted lines at the right side of Fig. I, and at this time the tubular bottle-receiving stems 12 will serve as vents, permitting air to flow from the bottles while the liquid is rushing into the mouths of said bottles. Each tubular bottle-receiving stem lies partly within the bottle associated therewith and partly beyond the mouth of said bottle, and when the bottle moves downwardly into the liquid, an open end of the tubular stem lies in the plane above the mouth of said bottle, thus permitting air to escape freely from the bottle to a point above the surface of the liquid. However, when the bottles travel upwardly at the left side of tank A (Fig. I), the tubular bottle-receiving members extend to points below the mouths of the bottles associated therewith, and as the bottles pass from the body of liquid in the tank, these tubular members serve as air vents which permit air to flow into the tilted bottles while the liquid is flowing from the mouths of said bottles.

I claim:

1. A bottle carrier comprising a traveler provided with a series of bottle-receiving stems adapted to lie within the bottles, each of said stems being provided with a cushion spring having a yieldable end member which lies beyond the outer end of the stem to prevent the bottles from striking said end of the stem.

2. A bottle carrier comprising a traveler provided with a series of bottle-receiving stems adapted to lie within the bottles, and cushion springs each of which surrounds one of said stems and extends to a point beyond the outer end thereof to engage the bottom of the bottle, each of said cushion springs being a helical member having its coils closely fitted together at points adjacent to the outer end of the stem with which it is associated.

3. A bottle carrier comprising a pair of sprocket chains, means for driving said sprocket chains, and bottle holders secured to said sprocket chains, each of said bottle holders including a connecting device uniting said chains and a row of bottle-receiving stems adapted to lie within the bottles, the inner end portions of the bottle-receiving stems of each row being secured to said con-

necting member and their outer ends being in approximately the same horizontal plane, and shock absorbers, associated with said bottle-receiving stems, adapted to lie within the bottles to prevent the bottoms of the bottles from striking the outer ends of said stems.

4. A bottle conveying device comprising a slideway, and a yieldable bottle pushing device for moving bottles along said slideway, said bottle pushing device including bottle pushers in the form of bottle receiving stems adapted to lie within the bottles and shock absorbers associated with said stems, said 15 shock absorbers being extended from said stems to yieldingly engage the inner faces of the bottles.

5. A machine of the character described comprising a slideway, and a bottle pushing device for moving bottles along said slideway, said bottle pushing device including bottle pushers in the form of a series of bottle-receiving stems adapted to lie within the bottles, and shock absorbers 25 extending from the outer ends of said stems so as to engage the inner faces of the bottles and to push said bottles along said slideway.

6. A machine of the character described comprising a slideway, and a bottle carrier 30 including a pair of sprocket chains, connecting devices uniting said chains, rows of bottle-receiving stems adapted to lie within the bottles, the inner ends of the bottle-receiving stems of each row being secured to

one of said connecting members, springs extending from the outer ends of said stems to serve as shock absorbers, said stems extending downwardly at points adjacent said slideway so that the bottles held thereby are free to drop onto and slide along said slide- 40 way, and the shock absorbers being arranged to engage the inner faces of the bottles to push said bottles along said slideway.

7. A bottle carrier comprising a flexible traveler, bottle holders secured to said flexible traveler, and means for guiding said traveler and bottle holders to tilt the bottle holders at a predetermined point, thus permitting the bottles to drop from the carrier, a portion of said carrier being in the path 50 of a portion of the tilted bottle holder at said predetermined point so that said portions will engage each other to shake the tilted bottle holder at said predetermined point.

8. A bottle carrier comprising sprocket chains, bottle holders connecting said sprocket chains, and means for guiding said sprocket chains and bottle holders to tilt the bottle holders at a predetermined point, thus 60 permitting the bottles to drop from the carrier, a portion of the tilted bottle holder being located in the path of a portion of another bottle holder so that the last mentioned bottle holders will strike each other 65 at said predetermined point to release the bottles from the tilted bottle holder.

JOSEPH W. DAWSON.
